UNITED STATES PATENT OFFICE

MAX OBERLIN, OF DARMSTADT, GERMANY

PROCESS FOR THE PRODUCTION OF 1-(PARA AMINOPHENYL)-2-METHYLAMINO-
PROPANOL-1

No Drawing. Application filed July 19, 1930, Serial No. 469,265, and in Germany August 7, 1929.

It is well known that the secondary alcohol-group of 1-phenyl-2-methylamino-propanol-1 is very reactive, when brought into contact with weak oxidizing agents (see e. g. E. Schmidt, Arch. of Pharm. 252, 1914, page 89).

By the present invention it has been shown that in contradistinction to these facts 1-phenyl-2-methylamino-propanol-1 is not destroyed by the action of cold nitric acid, but transformed into several nitro-derivatives. By the action of nitric acid of a specific gravity of 1.4 on the mentioned starting product 1-(para nitrophenyl)-2-methylamino-propanol-1 is formed. Instead of nitric acid of the above mentioned strength a mixture of nitric and sulfuric acid (sp. g. 1.8) may be used, the process being carried out in quite the same way. Care must be taken not to exceed a temperature of the reaction mixture of about +30° C. This can be done by any of the well known methods of cooling.

The so formed 1-(para nitrophenyl)-2-methylamino-propanol-1 is transformed to the corresponding amino-compound by any of the well known methods of reducing nitro-groups. The reduction may be carried out e. g. by hydrogen in statu nascendi (produced by any well known manner, e. g. by the addition of a metal to an acid) or by molecular hydrogen in connection with the use of catalysts, etc., as will be illustrated in the following examples.

As to the use of the new compound it may be pointed out that as is well known the 1-phenyl-2-methylamino-propanol-1 is used against respiration defects; the amino-derivative of the afore-mentioned body has the advantage of being less poisonous.

(1) 50 parts of normal nitrate of 1-phenyl-2-methylamino-propanol-1 are successively added to a mixture of 50 volume-parts sulfuric (sp. g.=1.84) and 50 volume parts ni-

tric (sp. g.=1.4) acid, care being taken that the temperature does not exceed 30° C. During the addition of the substance the mixture is stirred and after solution has taken place which will be a short time after adding the 50 substance the reaction product is poured on 125 parts ice which operation results in the crystallization of the nitrate of the nitro-product. After settling of some hours (say 2-3) the crystallization-product is isolated 55 by suitable means, e. g. filtered with suction, washed with water and dried by means of a vacuum or at a temperature not to exceed 100° C. 40 parts of raw-products are obtained which preferably consist of the nitrate of 1-para nitrophenyl-2-methylamino-propanol-1; this is proved by the oxidation, whereby the para-nitro-benzoic acid of a melting point of 238° C. is obtained. By recrystallizing the raw-product the pure normal 60 nitrate of 1-(para nitrophenyl)-2-methylamino-propanol-1 is obtained which melts under decomposition at about 171-173° C. The corresponding base crystallizes from ether in small faint-yellow needles of a melting point 65 of 105-107° C. The hydrochloric salt of this base forms white crystals of a decomposition point of about 266-268° C.

120 parts of the above described obtained nitrate are dissolved in 1500 volume parts of alcohol and are shaken in a closed vessel in presence of about 0.8 g. palladium-catalyst at a temperature of 40-50° C. in an atmosphere of hydrogen. After the consumption of slightly more than the amount of hydrogen which corresponds to three mols the hydrogenation is stopped; generally the shaking will take 5-25 hours' time; the shaking is carried out under a temperature of 40-50° C. The catalyst is separated and the solution is evaporated to dryness in a vacuum. The residue is dissolved in water and the free base is obtained therefrom in the ordinary way by the addition of alkali. Thereby 80-90 parts of dry raw-base are obtained. By recrystalliz- 85 90

Examples

(1) 50 parts of normal nitrate of 1-phenyl-2-methylamino-propanol-1 are successively added to a mixture of 50 volume-parts sulfuric (sp. g.=1.84) and 50 volume parts ni-

ing from chloroform-petrol-ether the normal 1-(para aminophenyl)-2-methylamino-propanol-1 is obtained as a white crystalline substance having a melting point of 114-116° C.

5 By neutralizing this base by means of hydrochloric acid, e. g. in aqueous solution, evaporating and recrystallizing from alcohol the mono-hydrochloride is formed which shows small needles of a decomposition point of 10 about 176-178° C.

(2) To a solution of 35 parts of raw normal 1 - (para nitrophenyl)-2-methylamino - propanol-1 in 500 volume parts of glacial acetic acid 300 volume parts of a solution of stan-

15 nous chloride in glacial acetic acid (corresponding to 120 parts tin) are added drop by drop at ordinary temperature, while the mixture is agitated. After the precipitation is complete the reaction-mixture is heated for

20 about one hour in a water-bath. It is then cooled by means of ice for some hours; the precipitated double salt of tin is separated by filtration and decomposed in aqueous solution by means of hydrogen sulfide; to this

25 mixture caustic soda is added, until the mixture shows a strong alkaline reaction; then it is extracted with ether. From the ether so-

30 lution the normal 1-(para aminophenyl)-2- methylamino-propanol-1 is obtained by evap-

35 oration of the ether in the form of crystals

showing a melting point of 114-116° C.

(3) 5 parts of hydrochloride of raw normal 1-(para nitrophenyl)-2-methylamino-

35 propanol-1 are dissolved in 200 volume parts of 5% hydrochloric acid; at a temperature of 0-5° C. afterwards 100 parts of sodium amalgam of 5% are added in portions of 5 parts

40 each, adding simultaneously to each portion of the amalgam 5 volume parts of hydro-

45 chloric acid of 25%. After 2 hours the solution is supersaturated with caustic soda and extracted with ether. From the ether solu-

50 tion by evaporation the 1-(para amino-

55 phenyl)-2-methylamino-propanol-1 is ob-

55 tained in the form of hard crystals of a melt-

60 ing point of 114-116° C.

Claims.

1. Process for the production of 1-(para aminophenyl)-2 - methylamino-propanol - 1 50 consisting in the treatment of a combination of 1-phenyl-2-methylamino-propanol-1 and a mineral acid, with nitric acid of sp. g. 1.4, at a temperature not exceeding 30° C., separating the resulting product, reducing the same, 55 and finally separating the free base.

2. The compound 1-(para aminophenyl)-2-methylamino-propanol-1 having a melting point of 114-116° C., soluble in water, more difficultly soluble in alcohol and chloroform, 60 very difficultly soluble in ether, insoluble in petrol-ether.

3. Process for the production of 1-(para aminophenyl)-2-methylamino-propanol-1, 65 consisting in the treatment of the nitrate of 1-phenyl-2-methylamino-propanol-1 with ni-

tric acid of sp. g. 1.4, care being taken that the temperature does not exceed 30° C., separating the resulting nitrate of 1-(para nitrophenyl) -2-methylamino-propanol-1, reducing it by one of the well known methods for 70 reducing nitro to amino compounds, and finally separating the free base after the addition of alkali.

In testimony whereof I have hereunto signed my name.

MAX OBERLIN.
